Primary Examiner — George D. Kirschbaum*Assistant Examiner* — Natasha Vujcic(74) *Attorney, Agent, or Firm* — Global Intellectual Property Agency, LLC; Daniel Boudwin(57) **CLAIM**

The ornamental design for a license plate holder, as shown and described.

DESCRIPTION

FIG. 1 shows a perspective view of the license plate holder.

FIG. 2 shows a front elevation view thereof.

FIG. 3 shows a rear elevation view thereof.

FIG. 4 shows a right side elevation view thereof.

FIG. 5 shows a left side elevation view thereof.

FIG. 6 shows a top elevation view thereof; and,

FIG. 7 shows a bottom elevation view thereof.

The broken lines in the drawings illustrate portions of the license plate holder which forms no part of the claimed design. The difference in shading in the figures indicates a contrast of color and does not depict any particular color, texture, or material.
